BARN WINDOW

James M. Mercer, Muskegon, Mich., assignor to
 Vento Steel Products Company, Muskegon,
 Mich., a corporation of Michigan

Application November 29, 1937, Serial No. 176,975

16 Claims. (Cl. 189—64)

This invention relates to windows of the type commonly known as barn windows, and in which a novel construction is provided for ventilation purposes, the ventilation being through a change of position or adjustment of the window so as to open for the passage of a ventilating draft of air of greater or less degree as may be required. The windows include metal frame members and with glass therein. The adjustable part of the window 5 may be tilted about its lower edge to different positions, so as to open the window to different positions, or such adjustable part of the window may be shifted to a lower position so as to open fully the space normally closed thereby. Likewise, such adjustable or shiftable part of the window may be removed entirely, if for any purpose it should be required.

My invention is directed to a very practical, useful, strong and durable, and at the same time, 20 economically constructed window for the attainment of the ends stated, as well as many others not at this time specifically pointed out, including a novel means for locking the window in closed position, but which will appear upon an 25 understanding of the invention had from the following description, taken in connection with the accompanying drawings, in which:

Fig. 1 is an elevation of the window in closed position.

30 Fig. 2 is a vertical section therethrough.

Fig. 3 is a vertical section of the upper part of the window, as shown in Fig. 2, in which said upper part or section of the window is tilted to partially open the same.

35 Fig. 4 is a section similar to Fig. 3, showing the upper section of the window tilted to its extreme open limit.

Fig. 5 is a vertical section similar to Fig. 2, in which the upper and adjustable part or section 40 of the window has been moved into a lower position so as to provide for full ventilation.

Fig. 6 is a fragmentary horizontal section at the upper part of the window, illustrating the novel lock which is used for locking the adjustable section of the window in closed position.

45 Fig. 7 is a fragmentary enlarged front elevation of said lock, and

Fig. 8 is a fragmentary section and plan view looking downwardly upon the combined lock and 50 brace, by means of which the window is held in the partially tilted position shown in Fig. 3.

Like reference characters refer to like parts in the different figures of the drawings.

The window is adapted to be installed in a 55 suitable window opening in a barn or the like, the

surrounding frame therefor being indicated at 1 in Fig. 2. In the construction of the window, an open frame, rectangular in outline, is provided, made from metal parts including a lower horizontal frame member 2 of Z-bar form, an 5 upper horizontal frame member 3 formed of a bar T-shaped in cross section, having a vertical flange from which the horizontal leg 4 extends substantially midway between the upper and lower edges of the flange 3. The sides 5 are likewise of T-cross section with vertical flanges extending inwardly as at 5a. The outer leg of the Z-bar lower member 2, the flanges 5 and the flanges 3 are in the same plane, the members of the frame being suitably welded or otherwise permanently secured together. The frame also includes, at a point substantially midway between the upper and lower horizontal members thereof, a third horizontal member 6, made from a Z-bar in which a vertical flange 7 extends upwardly from the web of the bar 6, best shown in Fig. 2. A vertical bar 8, likewise T-shaped in cross section, extends between the bars 2 and 6, dividing the lower part of the frame into panels in which glass panes 9 are secured in any suitable 25 manner. At the vertically extending flange of the lower bar 2, two sheet metal clips 10, of the form best shown in Fig. 2, are permanently welded or otherwise secured in spaced apart relation to each other.

30 Wings 11 of sheet metal are welded, riveted or similarly permanently secured at the upper portions and at the outer sides of the vertical flanges 5a of the vertical members 5 of the frame. Said wings are provided with inturned ledges 12 at 35 the free edges of the wings 11, said ledges extending downwardly and toward the frame of the window, at an angle to the vertical, as fully shown in Figs. 2 and 5, and are then continued in vertical extensions 13, at the lower part of 40 said wings.

Within the upper open part of the frame described is a tiltably adjustable and removable window section which includes a frame having a horizontal upper frame bar 14 of angle iron 45 form, vertical sides 15 of the same form, and a lower horizontal bar member 16 of Z-bar formation with an upwardly extending flange or leg 17. A vertical bar 18, T-shaped in cross section, extends between the upper and lower horizontal 50 members of the frame, dividing it into two panels in which the glass panes 19 are mounted. This upper window section, when in vertical position, as shown in Fig. 2, has the intermediate web of lower Z-bar 16, resting upon the upper edge of 55

the vertical flange or ledge 7 of the bar 6, and with the downwardly extending leg of said bar 16 in front of the vertical flange or ledge 7, and the upper horizontal bar 14 is against the lower portion of the flange 3 of the upper member of the window frame.

5 A bracket 20 is secured to the flange 17 of the bars 16 and has a horizontal leg extending over said flange, said bracket being located adjacent the middle of the upper window section. A bar 10 21, provided at one longitudinal edge with an upturned flange 22, is pivotally connected at one end at 23 to the upper horizontal bar 14 of the frame of the upper window section. A socket 24 15 is connected with the free end of the bar 21, extending downwardly therefrom, in which the upper end of a tubular rod 25 is connected, the lower end being bent toward and then extending underneath the bracket 20, to which it has a 20 pivotal connection. With this construction, the tubular member 25 with the attached bar 26 provides a bail-like handle which may be swung outwardly to the position shown in Figs. 3 and 4, or turned to lie substantially against the window 25 as in Figs. 1, 2 and 7.

A second and flat bar 26 at one end is reduced in width and formed with a hook 27. Said bar is longitudinally slotted at 28 for the major portion of its length. The bar 26 lies above the bar 30 21, and a guide 29, connected with the bar 21, passes through the slot 28, such guide at its upper end being provided with a head wider than the slot to prevent disconnection. A pin 30 is attached to the flange 4 in a position such that the hook 27 may engage therewith, as in Figs. 3 and 8. Normally with the window closed, or as in Figs. 1, 6 and 7, the handle member 25 and the bars 21 and 26, occupy the position wherein said bars lie over the frame bar 14 and underneath the flange 4. The two bars 21 and 26 are moved 40 so that the one lies directly under the other for practically their full lengths, as in Fig. 6, and the flange 22 at its inner end comes inside of the pin 30. The axis of the pin 30 is in direct alignment with the axis of the pivot 23, that is, it is on dead center therewith, whereby the window is held or locked against opening until the member 25 has been swung through substantially 90°. When it is swung in this manner, the hook 27 45 connects with the pin 30 and the locking flange 22 is moved out of engagement with said pin. Then, by pulling outwardly upon the tubular bar 25, the two bars 21 and 26 may be extended with respect to each other, the upper window section 50 taking the position shown in Fig. 3, and being held in such position by reason of the engagement of the hook 27 with the pin 30, and because the guide 29 has come to the outer end of the slot 28.

To open the upper window section to a still 60 further open position, the hook 27 is disengaged from the pin 30 and the upper window section tilted until the ends thereof rest against the ledges 12. The slotted bar 26 in such a position serves no purpose and it is moved to lie directly over the bar 21.

In a third position of the upper window section, as in Fig. 5, such upper window section has been 70 lifted to disengage the Z-bar 16 from the flange 7 of the similar bar 6, which has previously supported it, and the window is then carried downwardly until the bar 16 comes against the clips or brackets 10. The upper end portions of the upper window section are within the vertical extensions 13 of the ledges 12, holding the window section in place as fully shown in Fig. 5. It is

75 of course evident that by lifting the upper window section so as to disengage the bar 16 from the clips 10, it may be entirely removed.

The construction described is of a very practical form, relatively simple and easy to manufacture at low cost of fabrication. With such window structure, the extent or degree of ventilation may be changed as indicated. It is to be understood that the invention does not necessarily require the lower stationary part of the window, 10 but that all of the advantages of the window are attained, except the full open position such as shown in Fig. 5, if a window is made in which the window frame has for its bottom bar the bar 6, and all that is below it is not used. The invention therefore, is not to be limited to the specific disclosure shown, but is to be considered comprehensive of all forms of structure coming within the scope of the claims appended hereto which define the invention. 15

20 I claim:

1. A window, a window frame, a window section 25 tiltably mounted in said window frame to turn about its lower edge, means pivotally mounted on a vertical axis detachably connecting the upper part of said window section and the upper part of the window frame whereby said section may be tilted with respect to the window frame and held at a predetermined position said means also adapted to lock said section in a closed position, 30 and means carried by the sides of said window frame to support said tilttable window section in a further tilted position upon the disconnection of said first mentioned means from the window frame. 35

2. A window comprising an open window frame, a window section tiltably mounted thereon at its lower part whereby it may be tilted outwardly with respect to the window frame, a pin connected to the upper member of the window frame, 40 a bar having a hook at one end, said hook being adapted to detachably connect with said pin, means for slidably connecting said bar with the upper member of said window section whereby said section may be tilted to a predetermined 45 position and held thereon by said bar, wing members connected to the vertical sides of the window frame, having inturned supporting ledges at their edges farthest removed from the window frame, against which ledges the ends of said tilttable 50 window section may be brought to hold said window section in a further tilted position upon disconnection of said hooked bar from said pin.

3. In a window, a window frame, a window section including a frame and glass therein tiltably mounted at its lower edge portion on said window frame and adapted to be moved into position against the window frame or tilted away therefrom, a pin on the upper member of the window frame, a bar connected with the upper 60 member of said window section frame, a slotted bar over said first bar and having a hook at one end adapted to detachably connect with said pin, a member connected with the first bar and extending through the slot of said second bar 65 whereby the said bars may be slidably extended with respect to each other or moved to lie one over the other, and wing members secured to the vertical sides of the window frame, said wing members having inturned supporting ledges inclined downwardly and inwardly toward the window frame at the edges of said wings farthest from said window frame, as and for the purposes specified. 70

4. In a window, an open window frame, having 75

upper and lower horizontal frame bars and vertical end bars, said upper bar having a horizontal flange, a pin connected to said flange and extending downwardly therefrom, a tilttable window section comprising, a frame having horizontal upper and lower bars and vertical connecting end bars, the lower bar of said window section being mounted upon the lower bar of said window frame whereby the window section may be tilted 5 toward and away from the window frame, a bar having a horizontal flange and a vertical flange at one edge thereof pivotally mounted at one end on the upper member of said window section frame, a slotted bar lying over the horizontal 10 flange of said first mentioned bar, a member extending from the horizontal flange of said first bar through the slot in the second bar, said second bar having a hook adapted to be detachably connected with said pin, whereby said tilttable 15 window section may be tilted away from said window frame a predetermined distance or moved inwardly to close the opening in said window frame, and said first mentioned bar turned about its pivot to engage the vertical flange thereof 20 25 with said pin thereby locking the tilttable window section against movement.

5. In a window, an open rectangular window frame comprising, upper and lower horizontal frame bars, vertical end bars and an intermediate horizontal bar between said upper and lower horizontal bars, glass panes secured in the lower part of said frame between said lower horizontal bar and intermediate horizontal bar, a window section comprising a rectangular section frame tiltably and detachably mounted upon said intermediate bar, means connected with said tilting window section and detachably connected with the upper bar of said window frame for holding the tilttable window section in a predetermined tilted position, said means being detachable from the window frame to permit said window section to be tilted to a farther position, means connected with the sides of said window frame for supporting said tilttable window section in said farther tilting position, and means connected to the lower bar of the window frame for supporting the lower end of said tilttable and detachable window section on disengagement thereof from said intermediate horizontal bar 50 and lowering thereof to a lower position back of the lower part of said window.

6. In a window, an open window frame comprising, upper, lower and intermediate parallel horizontal bars and vertical end bars permanently secured together, glass panes in the lower part of said frame between said lower and intermediate frame bars, a window section comprising, an open frame having upper and lower horizontal frame bars and vertical end bars secured together with glass panes therein, said lower bar of the window section frame having a tilting and detachable mounting on the intermediate bar of said window frame, sheet metal wings connected to the vertical bars of said window frame between the upper and intermediate horizontal window frame bars, said sheet metal members having downwardly and inwardly extending inturned supporting ledges at the edges thereof farthest from the window frame, said ledges terminating in vertical extensions spaced from the window frame, and supporting members on the lower bar of said window frame, whereby said tilting window section may be tilted to rest against said ledges or may be lifted to disengage from said intermediate horizontal bar of

the window frame and bodily moved downwardly to engage at its lower edge with said supporting members and be held at its upper end by said vertical extensions to said supporting ledges, as and for the purposes specified. 5

7. In a window, an open window frame having spaced apart horizontal bars and vertical end bars connected therewith, a tilting window frame, tiltably mounted at its lower side on the lower horizontal bar of said open window frame, a bar pivotally mounted at one of its ends at the upper edge of said tilting window section, a slotted bar over the first bar having a pivotal connection at one end with the upper frame member of said window frame, a member on said first bar extending through the slot of said second bar, whereby said window section may be moved to closed position or to tilted position, and means on said first mentioned bar adapted to engage with the upper bar of said open window frame on turning said first mentioned bar about its pivot to a position where it lies in alinement with the upper member of said window frame, thereby locking the tilting window section in closed position. 10 15 20

8. In a window, an open rectangular window frame having horizontal upper and lower frame members and vertical end members, said upper horizontal frame member having a horizontal flange, a pin connected to and extending downwardly from said flange, a window section comprising an open frame having horizontal upper and lower frame members and vertical end members, said lower member of said window section frame having a tilting mounting on the lower member of the window frame, a bar pivotally mounted at one end of the upper frame member of said tilting window section, said bar having a horizontal flange and a vertical flange at one edge thereof, and said bar being adapted to swing to a position over the upper frame member of said tilting window section or extend outwardly at right angles therefrom, a flat bar longitudinally slotted the major portion of its length and between its ends lying over the horizontal flange of the first bar, a headed member connected to said horizontal flange of the first bar extending through the slot of said flat bar, said flat bar at its free end being formed with a hook adapted to detachably connect with said pin, the vertical flange on said first mentioned bar being located at an edge thereof such that it is swung around said pin so as to position the pin between said flange and the pivotal axis of said bar when said bar is moved to a position over the upper member of said tilting window section. 30 35 40 45 50 55

9. A window comprising the elements in combination defined in claim 1, combined with a handle member associated with said first named means adapted to be rotated in a horizontal plane through an arc of substantially 90° to release the locking means. 60

10. A window structure comprising, an open frame, a sash therefor having a detachable pivotal connection at its lower edge with said frame, and supporting means extending inwardly from said frame and engageable with said sash to support said sash when pivoted inwardly with respect to said frame, said supporting means being spaced sufficiently from said frame to permit said sash to be moved bodily downward between said supporting means and said frame. 65 70

11. The elements in combination defined in claim 10, combined with means for suspending said sash in lowered position with its upper edge above the lower edge of said supporting means. 75

12. A window construction comprising, an open rectangular frame, a sash therefor having detachable pivotal connection at its lower edge with said frame, vertical shielding members extending inwardly from said frame outside the respective vertical edges of said sash, and supporting means on said shielding members engageable with said sash to support the sash in inward pivoted position relative to said frame, said supporting means being spaced sufficiently from said frame to permit said sash to be bodily lowered between the supporting means and the frame.
13. The elements in combination defined in claim 12, combined with means for suspending said sash in lowered position with its upper edge in engagement with said supporting means.
14. The elements in combination defined in claim 10, combined with detent means on said frame, a lever pivotally mounted on a vertical axis on said sash, and means actuated by said lever and coacting with said detent means on said frame to both lock the swinging edge of said sash in close engagement with said frame and to retain the swinging edge of said sash in a position intermediate engagement with said frame and that position in which it is supported by said supporting means.
15. A window comprising a window frame, a window section tiltably mounted thereon, two elongated bars located on the top edge of said section and slidably with respect to each other, a pin extending from the top of said frame, said bars adapted to cooperate with said pin to stop said section in a predetermined tilted position.
16. A window comprising the elements in combination defined in claim 15, combined with wing members extending from either side of said frame and having flanges integral therewith against which flanges said section may be brought to hold same in a further tilted position upon disconnection of one of said bars from said pin.

JAMES M. MERCER.
